UNITED STATES PATENT OFFICE.

JOHN P. FLETCHER AND FRANK P. STONE, OF CARLISLE, PENNSYLVANIA.

COMBINATION DENTAL CHAIR AND ENGINE.

Application filed November 22, 1924. Serial No. 751,721.

(GRANTED UNDER THE ACT OF MARCH 3, 1883, 22 STAT. L., 625.)

To all whom it may concern:

Be it known that we, JOHN P. FLETCHER and FRANK P. STONE, citizens of the United States, and residents of Carlisle, in the 5 county of Cumberland and State of Pennsylvania, have invented a new and useful Improvement in a Combination Dental Chair and Engine, of which the following description, in conjunction with the accompanying drawings, is a specification.

This invention described herein may be used by the Government, or any of its officers or employees in prosecution of work for the Government, or by any other person 15 in the United States, without the payment to us of any royalty thereon.

This invention relates to dental appliances more particularly it is directed to a dental chair and engine, combined in a manner to 20 effect a unitary structure.

One of the objects of this invention is to provide a dental engine of the manually operable type, susceptible of detachable engagement with the supporting tripod of an 25 army field dental chair and capable of being rotatably suspended immediately beneath the head of the tripod within the area embraced by its spread legs, for adjustment to any position desired by the operator.

Another object of this invention is to 30 effect a dental engine of the character specified having a driving means in the nature of a spring actuated link mechanism interposed between the fly wheel and operating 35 treadle which insures a smooth, continuous and uniform power transmission to the flexible shafting and the dental instrument with which it is engaged.

Other objects of this invention are, to 40 provide a combined dental chair and engine of compact construction, which may be quickly positioned for service and conveniently disassociated for transportation purposes and to produce an assembly of the 45 type indicated which is simple in construction, of comparatively few parts and particularly adapted for the rigorous service imposed by army field usage.

With these and other objects in view this 50 invention consists in certain novel details of construction, combination and arrangement of parts to be more particularly hereinafter set forth and claimed.

Briefly stated, this invention comprises a tripod adapted to support a dental chair of the army field type, a forked standard 55 detachably and rotatably suspended beneath the head of the tripod, a fly wheel mounted in the standard, a driven pulley likewise journaled in the standard and above the fly wheel to which it is belted, a flexible shafting 60 coupled with the driven pulley, a foot treadle and a link driving mechanism interconnecting the treadle with the fly wheel, such mechanism including a driving lever 65 pivotally connected at one end to the standard and at its free end to the upper extremity of the link carried by the treadle, a pitman interconnecting the fly wheel crank and driving lever and a helical spring between 70 the pitman and the pivotal connection of the driving lever, the spring functioning to overcome dead center and assist in rotation of the fly wheel.

Referring to the accompanying drawings 75 in which corresponding parts are indicated by similar reference characters:

Fig. 1, is a perspective view illustrating 80 the dental engine forming the subject matter of this invention, operatively combined with a dental chair of the army field type.

Fig. 2, is an end elevation of the dental engine detached from the chair.

Fig. 3, is a perspective view of the dental engine detached from the chair.

Fig. 4, is a fragmentary sectionized detail of one leg of the tripod, the angle bracket affixed thereto and swivel connection between engine frame and bracket, and

Fig. 5, is a fragmentary sectionized detail 90 illustrating the lower end of engine-frame, anchoring plate carried thereby and base of treadle.

As the space at the disposal of the various army units when in the field is more or less 95 limited it is highly important that all material for army usage be constructed so as to permit of minimum space transportation.

Heretofore, the dental engines utilized by the army have been of conventional type 100 and while answering the purpose were objectionable because of their bulk. It is therefore among other things, the aim and purpose of this invention to provide a combination dental chair and engine of compact construction which may be arranged for

shipment in but a part of the space previously required for this purpose.

In the illustrated embodiment characterizing this invention there is shown a dental chair of the army field type comprising a body portion involving a standard (1) adjustably supporting a seat (2), back (3) and head rest (4). The body portion is mounted upon a tripod comprising a head (5) to which the standard (1) of the body portion is hinged and legs (6), (7) and (8). As the preceding forms no part of the present invention it is referred to for descriptive purposes only.

Coming now to the invention under consideration reference being had to Figures 2 and 3 of the drawings, there is shown an engine frame embodying head plate (9) and parallelly arranged forks (10) and (11). The lower ends of forks (10) and (11) are formed with lips (12) which are provided with registering openings (13) to receive the threaded shank (14) of extension plate or bolt (15). This bolt when in position and suitably anchored with a nut (16) secures the lipped ends of the forks (10) and (11) in binding relation and at the same time provides an anchorage for the base (17) of a foot treadle (18) as clearly shown in Figure 3 of the drawings.

Rotatably journaled between the parallel forks (10) and (11) is a fly wheel (19) suitably grooved to receive belt (20) which circumscribes the fly wheel and passes over a pulley (21). This pulley (21) is keyed to a stub shaft (22) journaled above the fly wheel between forks (10) and (11).

A flexible shafting (23) coupled as at (24) to stub shaft (22) enables rotary movement of the fly wheel to be transmitted to the flexible shafting and thence to the dental instrument (not shown) adapted to be attached to the free end of said shafting as will be readily understood without further discussion.

To actuate fly wheel (19) foot treadle (18) is connected through a link mechanism with crank (25) of the fly wheel. This link mechanism comprises a link (26) hinged at one end to the free end of treadle (18) and at its opposite end to the outer extremity of driving lever (27). The free end of driving lever (27) is pivotally connected to stud (28) extending laterally from the fork (11) of the standard as clearly shown in Figures 2 and 3 of the drawings.

A pitman (29) interconnects driving lever (27) with crank (25) of the fly wheel, one end of the pitman being connected to the crank, the free end to driving lever (27) at a point adjacent its outer end. With the link mechanism arranged in this manner it will be evident operation of the foot treadle will impart rotary movement to the fly wheel.

In order to insure proper positionment of the crank (25) for each power thrust of pitman (29) a helical spring (30) of suitable length is connected at one end to a pin (31) projecting from the end of stud (28). The free end of spring (30) is attached to pin (32) carried by pitman (29) and located thereon at a point adjacent its crank end. This spring not only serves to overcome dead center but by virtue of its upward pull on the crank (25) tends to assist rotation of the fly wheel and thus assures smooth and uniform power transmission from the foot treadle to the flexible shafting.

To enable the dental engine to be detachably connected with the chair and rotatably suspended within the area embraced by the spread legs of its tripod, head plate (9) of the engine frame is formed with an opening (33) for the passage of an externally threaded swivel stud (34) upon which are positioned washers (35) and retaining nut (36).

A bracket (37) including legs (38) and (39) is mounted on the under surface of tripod leg (6) adjacent its upper end for co-operation with stud (34) of the engine frame as shown in Fig. 4 of the drawing. One leg of the bracket (37) is longitudinally slotted as at (38') for the passage of suitable fastening elements by which it is adjustably affixed to the tripod leg. The remaining leg (39) of the bracket underlies head (5) of the tripod and is bifurcated as at (40), to embrace the stud (34), the furcations of the leg (39) passing between washers (35) as clearly shown in Figure 4 of the drawing.

When the stud (34) has been positioned between the furcations of leg (39) as aforesaid and nut (36) properly adjusted the engine frame while free to rotate, will be securely clamped to the bracket.

In conclusion it will be manifest this invention provides an arrangement by which a dental engine may be readily combined with a dental chair of the army field type and when operatively positioned will be out of the way and disposed for convenient actuation by the operator.

Although in the foregoing certain elements have been described as best adapted to perform the functions allotted to them, nevertheless it is to be understood that various minor changes may be resorted to within the scope of the appended claims without departing from or sacrificing any of the principles of this invention.

Having described our invention what we claim as new and wish to secure by Letters Patent is:

1. The combination with a dental chair including a supporting tripod; of a dental engine suspended from the tripod within the area embraced by its spread legs.
2. The combination with a dental chair

- including a supporting tripod; of a dental engine detachably connected to the tripod and suspended therefrom within the area embraced by its spread legs.
- 5 3. The combination with a dental chair including a supporting tripod; of a dental engine detachably connected to the tripod and rotatably suspended therefrom within the area embraced by the spread legs of the 10 tripod.
- 10 4. The combination with a dental chair including a supporting tripod; of a dental engine in detachable engagement with one leg of the tripod and suspended within the 15 area embraced by the spread legs of the tripod.
- 15 5. The combination with a dental chair including a supporting tripod; of a dental engine in detachable engagement with one 20 leg of the tripod and rotatably suspended therefrom within the area embraced by the spread tripod legs.
- 25 6. The combination with a dental chair including a supporting tripod; of a dental engine, means to swivelly and detachably suspend the dental engine from the upper end of one leg of the tripod.
- 30 7. The combination with a dental chair including a supporting tripod; of a dental 35 engine embodying an engine standard and means to detachably suspend the engine standard from the upper end of one of the tripod legs and within the area embraced by said legs when spread and a dental engine 40 carried by said frame.
- 40 8. The combination with a dental chair including a supporting tripod; of a bracket 45 affixed to one leg of the tripod, an engine standard and means to detachably connect the upper end of the standard to the bracket to effect suspension of the standard within the area embraced by the spread legs of the tripod, and a dental engine operatively associated with the standard.
- 45 9. The combination with a dental chair including a supporting tripod; of a bracket 50 affixed to one leg of the tripod, an engine standard and means to detachably and rotatably connect the upper end of the standard to the bracket to effect suspension of the standard within the area embraced by the spread legs of the tripod, and a dental engine operatively associated with the standard.
- 55 10. The combination with a dental chair including a supporting tripod; of an angle 60 bracket adjustably connected to the upper end of one of the legs of the tripod, an engine standard, means in connection with the upper end of the standard to detachably engage the bracket and a dental engine operatively associated with the standard.
- 65 11. The combination with a dental chair including a supporting tripod; of a bracket 65 affixed to the upper end of one leg of the
- tripod, an engine standard, means rotatably affixed to the upper end of the engine standard to detachably engage the bracket, and a dental engine carried by the standard.
- 70 12. The combination with a dental chair including a supporting tripod; of a forked standard suspended at its upper end from one leg of the tripod, a fly wheel mounted in the standard, a flexible shafting operatively connected with the fly wheel, a foot treadle carried by the standard and a driving mechanism interposed between treadle and fly wheel.
- 75 13. The combination with a dental chair including a supporting tripod; of a forked standard, coacting means on the forked standard and one leg of the tripod to detachably and rotatably suspend the standard within the area embraced by the spread legs of the tripod, a fly wheel mounted in the standard, a flexible shafting operated by the fly wheel, a treadle carried by the standard and a driving mechanism interposed between the treadle and fly wheel to effect operation of the latter.
- 80 14. The combination with a dental chair including a supporting tripod; of a forked standard, coacting means on the upper end of the standard and one leg of the tripod to detachably and rotatably suspend the tripod within the area embraced by its spread legs, a fly wheel mounted in the standard, a flexible shafting operated from the fly wheel, a foot treadle affixed to the lower end of the standard and a driving mechanism interposed between the fly wheel and foot treadle.
- 85 15. The combination with a dental chair including a supporting tripod; of an angle bracket secured to one leg of the tripod, a forked standard, a bolt rotatably mounted in the upper end of the standard, means on the bolt to detachably engage the bracket, a fly wheel mounted between the forks of the standard, a flexible shafting operatively connected with the fly wheel, a foot treadle mounted on the lower end of the standard and a driving mechanism between the foot treadle and fly wheel.
- 90 16. The combination with a dental chair including a supporting tripod; of an angle bracket secured to one leg of the tripod, a forked standard, a bolt rotatably mounted in the upper end of the standard, means on the bolt to detachably engage the bracket, a fly wheel mounted between the forks of the standard, a flexible shafting operatively connected with the fly wheel, a foot treadle mounted on the lower end of the standard and a driving mechanism between the foot treadle and fly wheel, such mechanism including means to overcome dead center and assist in rotation of the fly wheel.
- 95 17. A dental engine comprising a standard, a fly wheel carried by the standard, a driven shaft operatively connected with the

fly wheel, a foot treadle carried by the standard and a driving mechanism interposed between the foot treadle and fly wheel, such mechanism including means to overcome dead center and assist in rotation of the fly wheel.

18. A dental engine comprising a standard, a fly wheel carried by the standard, a driven shaft operatively connected with the fly wheel, a foot treadle carried by the standard and a driving mechanism interposed between the foot treadle and fly wheel, such mechanism including a link construction cooperating with a reaction spring to overcome dead center and assist in rotation of the fly wheel.

19. A dental engine comprising a standard, a fly wheel carried by the standard, an

operating crank for the fly wheel, a flexible shafting driven by the fly wheel, a foot treadle carried by the standard and a driving mechanism interposed between the foot treadle and fly wheel, such mechanism including a driving lever pivoted at its inner end to the engine standard, a connecting link having one end hinged to the foot treadle, the other end to the outer end of the driving lever, a pitman interconnecting driving lever and fly wheel crank and a helical spring affixed to the inner end of the driving lever and lower end of pitman, to overcome dead center and assist in rotation of the fly wheel.

JOHN P. FLETCHER.
FRANK P. STONE.
